MEANS FOR INCREASING THE EFFECT
OF STATIC

Philip M. Haffcke, Washington, D. C.

Application June 26, 1936, Serial No. 87,404

1 Claim. (Cl. 179—171)

(Granted under the act of March 3, 1883, as
amended April 30, 1928; 370 O. G. 757)

This invention relates to increasing the ratio of the amplitude of an impulse produced by static to the amplitude of a signal wave current received concomitantly with such impulse.

It is the object of this invention to provide a circuit whereby there will be effected a disproportionate amplification of waves received thereby when the amplitude thereof is above a predetermined value, thereby materially increasing the difference between a signal wave and a static-produced wave to facilitate the suppression of the latter in subsequent stages of the receiving set circuits.

In the drawing:

Fig. 1 is a graph showing the relative amplitudes of a signal wave and a wave due to static in the input circuit and also their relative magnitudes in the output circuit of a tube;

Fig. 2 shows a conventional circuit for an amplifier tube; and

Fig. 3 shows the circuit of Fig. 2 modified to accomplish the objects of this invention.

Heretofore, it has been the practice to decrease as much as possible the ratio of static to signal, but with certain systems of static suppression the greater the ratio of static to signal the more effectively will the suppressing system eliminate the undesired static component of the received energy. Therefore, when using a suppressing system such as has been mentioned, it is desirable to increase the disparity between the peaks of the signal wave and the static in the input of the suppressing system, and this is effected by the present invention.

It is, of course, understood that, for the present purpose, there must be a measurably greater amplitude to the static surges than to the signal, which makes feasible a differential amplification of the energy components from the two sources. The principle is simple and requires no specially built tubes or changes in circuits other than a change in the grid bias in the stage in which this system is to be incorporated. Ordinarily it is preferable to use a tube having variable transconductance (variable mu), such as are known under the trade numbers of 35, 58, and 78. It is well known that the E_g — I_p curve of such tubes is similar to curve A in Fig. 1, whereas the corresponding curve of a linear amplifier is like B in Fig. 1. It is apparent that when a tube having the characteristics shown by curve A, Fig. 1, is biased to operate about the point O on the lower knee of the curve the portion of the curve included in a received signal represented by 4 will result in an output wave such as is

shown at 5. However, if a static-produced wave having amplitude indicated by 6 in Fig. 1 is received concomitantly therewith, the corresponding output component will be defined by 7. It will be noted that the ratio of amplitude 7 to 5 amplitude 5 is very much greater than is the ratio of amplitude 6 to amplitude 4 and, therefore, the suppression of 1 will be facilitated in systems of the type above mentioned.

Fig. 2 illustrates a well known circuit for one amplification stage of a radio receiver. The variable mu tube has a cathode 8, control grid 9, screen grid 10, and anode 11. The input circuit includes inductance 12 and capacity 13 in parallel and a resistance 14 by-passed by condenser 15. Resistor 16 is in the screen grid circuit and by-pass condenser 17 is connected between the screen grid 10 and cathode 8.

Fig. 3 shows the circuit of Fig. 2 modified to operate according to the present invention. The principal change is in connecting resistor 18 to the screen grid circuit between resistor 16 and the source of positive potential and to the cathode circuit between capacity 17 and resistor 14. However, the value of resistor 14 is preferably changed so that the resistors 14 and 18 constitute a voltage divider to supply the proper bias to cathode 8 to insure that it is operated about the desired point on the E_g — I_p curve. In case the receiving set were originally designed to use a linear amplifier tube in the chosen stage, such tube should be replaced by a variable mu tube and the resistor 18 added. Where the set uses a variable mu tube in the stage to be changed the resistor 18 may be added or in some cases the value of resistor 14 may be increased to, say, 25,000 ohms or more, even up to one megohm, and the mode of operation herein described will result.

Some overall gain up to the output of this stage will be sacrificed from the standpoint of signal intensity, but the overall gain of strong static impulses will prove to be increased to practically the same amplitude as though the stage still had the usual linear characteristic.

All tubes show the variable mu characteristic to some degree when biased to operate on either the upper or lower knee of the E_g — I_p curve, and by careful selection of applied grid voltages they may be used to serve my present purpose; but those types known as having remote cut-off, or variable mu, have much greater working range at the lower knee of the said curve and are best for use in stages where the input voltages are of

greater amplitude, if a reasonable percentage of the signal is to be retained.

This invention may be manufactured and used by or for the Government of the United States of America for governmental purposes without payment of royalties thereon or therefor.

I claim:

In a radio amplifying system, a variable transconductance amplifier vacuum tube having a cathode, a control grid, an anode and a screen grid, a first resistance connected between said screen grid and a source of positive potential,

an input circuit connected to said control grid and including a second resistance connected to said cathode, and a constant third resistance connected to said source of positive potential and to said cathode between said tube and said second resistance, said second and third resistances acting as a voltage divider to apply to said input circuit biasing potentials to amplify disproportionately the higher amplitude peaks as compared with those of lower value. 5 10
